UNITED STATES PATENT OFFICE

1,993,461

MARKING MACHINE

George Stiegler, Cincinnati, Ohio

Application December 17, 1932, Serial No. 647,733

14 Claims. (Cl. 101—101)

My invention relates to machines designed particularly for marking articles in laundries or marking goods with style and lot numbers, and many other uses which will be apparent. It is an improvement on my marking machine disclosed and claimed in my prior Patent No. 1,891,656, issued December 20, 1932, and, in common with that invention, has for its objects the provision of a relatively small compact machine, instead of the usual large cumbersome marking apparatus used in laundries and the like, the provision of automatic inking means for the marking device, and the easy setting of various marking characters to marking position on the marking means.

Objects peculiar to my present improvement are more particularly related to the marking device, and to the means whereby the marking device swings the inking device aside. The inking device is substantially the same as the one fully disclosed and claimed in the above mentioned patent.

One of these objects is to provide, by a simple construction, a readily operated mounting for the marking dial or dials, both as regards setting of the dial or dials, and as regards movement of these collectively in the marking operation.

Another object is to provide for ready disassembly of the marking device from the frame and the inking device, and of the dials from the marking device.

Other objects will appear in the course of the following description, illustrated by the accompanying drawing, in which—

Figure 1 is a side elevation of a marking machine embodying my invention.

Figure 2 is a partial vertical section of same on line 2—2 of Figure 1.

Figure 3 is a detail perspective view of one of the dial friction washers.

Figure 4 is a similar view of the base.

Figure 5 is a partial section, enlarged, on line 5—5 of Figure 1, showing the base latch.

The inverted U-shaped frame 1 has a vertical slot 2 in one side and a vertical groove 3 in the inner face of its opposite side. A tube 4 is secured to the top of frame 1, through which operating rod 5 extends to slide up and down through the frame top. This rod 5 has a handle 6 fixed by a nut 6a on its upper end. The handle is hollow and the tube 4 telescopes therein, the handle and tube enclosing a helical spring 7 around the rod 5, normally holding the rod in raised position.

Within the frame 1 is the inverted U-shaped

dial-carrying frame 8 with its top fixed on the lower end of rod 5. The plate 9 carrying the inking mechanism is pivoted by screws 10 on the rear upper parts of the sides of the dial-carrying frame 8, to swing outwardly and then inwardly, being yieldingly held in by the leaf spring 11. This inking mechanism is fully disclosed and claimed in the above-mentioned prior patent, and it is sufficient to state that the pad carrier 12 is pivoted on the lower end part of this plate to swing the inking pad 13 under action of a rack 14 meshed with segment 15 on the pad carrier and sliding up and down on plate 9, by a suitable engagement of the dial carrier 8, so that the pad swings upward and inward as the carrier 8 descends, then is released by the carrier 8 and is swung downwardly and outwardly by action of tension spring 15 on rack 14.

In said prior patent, a finger on plate 9 is engaged by the dial carrier to swing the inking device outward. In my present improvement rollers 16 are journaled on studs on the inner sides of ears on the lower corners of the plate 9, and curved edge portions 17 of the dial carrier engage these rollers for the same purpose; the action being to withdraw the inking pad from the path of the descending marking dials after the pad has contacted the dial faces of the mechanism swinging it as above referred to.

The dials 18, here shown as eight in number, are mounted for coaxial but independent rotation on the shaft 19, which has a key-way 20. Friction washers 21 are interposed between the dials 18 and have key projections 22 in the shaft key-way 20. The shaft 19 is journaled in the lower end parts of the legs of the inverted U-shaped carrier 8 before described. Ears 23 projecting about midway of the height of the front of this carrier 8 support a transverse pin 24 on which the pawls 25 are pivoted, being spaced along the pin 24 by washers 26 and from the ears by washers 27. The pawls 25 have upwardly and forwardly projected handles 28 which diverge laterally for easy selective engagement of the operator's fingers therewith. The pawls 25 also have rear ears from which respective tension springs 29 are stretched upwardly and rearwardly to a pin 30 mounted transversely in the upper front part of the dial carrier frame 8. The lower end 31 of each pawl extends rearwardly to engage in any one of the notches 32 between the character-bearing face portions 33 of the dial periphery.

Washers 26a are interposed between the group of dials 18 and the sides of the dial carrier 8.

Pressing backwardly on a pawl handle 28 disengages the pawl end 31 from a notch 32, releasing the respective dial 18 to be turned with the shaft 19 by the frictional engagement of the adjacent friction washers with the dial. By this means any one of the dials may be set relatively to the other dials to present different combinations of transversely aligned characters at the bottom of the series of dials, to be inked by pad 13 as the dials descend, and then to contact the marking surface after the pad has been moved out of the way by the frame and roller engagement before described.

The dial carrier 8 is guided at one side by having a stud 33 thereon sliding in a vertical groove 3 of the frame 1, and at the other side by the shaft 19 extending out through the slot 2 of the frame 1. At the same time, the shaft 19 is held from axial displacement from the dial carrier 8 by an annular flange 34 around and preferably integral with the shaft between the carrier 8 and the adjacent side of the frame 1 where the shaft extends through the frame slot 2. On the outer end of the shaft 19 at this side is the manipulating knob 35 fixed thereon, preferably integral with the shaft.

The frame 1 has a base plate 36 which has an aperture 37 with locating points 38 at its opposite edges, which serve to locate the machine at the area to be marked. This plate 36 is hinged to the frame 1 so that it may be swung down and aside as indicated by the dotted lines in Figure 1, allowing removal of the marking device from the frame 1 after unscrewing the nut 6a at the top of the handle. The nut 6a is in the form of a cap for the handle 6, with a hub 6b to cause the user to correctly grasp around the handle.

The base plate hinge is formed by screws 39 in the opposite outer sides of the frame 1, near their rear edges, pivoting the upper end parts of rear lugs 40 which extend up from the plate 36 and straddle the frame 1. It is latched in closed position by shorter front lugs 41 extending up from the plate, straddling the frame 1, each having a hole 42 in its upper end part, and small balls 43 embedded in holes in the frame sides, over which the lugs 41 spring, with the balls entering the holes, or allowing the lugs to spring off the balls for opening. The plate 36 also has portions 44 extending up between the lugs to such short distance as will clear the shaft 18 in its lowest position, which reinforce the plate and its lugs and afford the plate firm bearings against the respective sides of the frame 1.

The inking mechanism may be removed as a unit from the frame by removing its pivot screws 10 and slipping it from under its spring 11. The marking mechanism being also easily removable by the means as just described, it will be seen that the entire device is readily taken apart for access to its interior parts. Swinging of the base plate 36 aside permits access to the pad and dials even if the marking mechanism is not removed from the frame.

The setting of the dials is most easily done by swinging the base plate to open position, grasping the handle 6 in the left hand with the bottom of the machine upward with the dials in easy view of the operator, bringing the knob 35 at the right for turning with the right hand while the thumb of the left hand depresses one or the other pawl handles 28 to release the dial 18 required to be turned. In this position the characters are right side up to the operator, and easily read. The extension of the dial shaft through the slot in the

frame, with the knob at the side, is an especially important factor in dial setting in my compact and simple machine. It affords a practical and very simple means for this in conjunction with the friction disk arrangement to hold all but the released dial against rotation. This is in marked contrast with machines having complicated systems of keys for setting the dials, and enables me to provide a truly hand carried stamp, whereas the more complicated and heavy machines are hardly suitable for easy handling and many of them are not truly portable machines.

I have specifically disclosed and described my preferred machine, but I am not to be understood as being limited to such precise disclosure, and what I claim and desire to secure by Letters Patent, is:

1. A marking machine comprising a frame, marking means slidable toward and from the base end of the frame, bearing a row of characters, and a base member mounted on said frame to extend across said base end or to move on said frame transverse to the row of characters aside from said end and up alongside said frame, allowing marking contact of the marking means when across the frame, and allowing increased facility of access to said marking means when moved aside.

2. A marking machine comprising a frame, marking means slidable toward and from the base end of the frame, bearing a row of characters, and a base member mounted on said frame to extend across said base end or to move on said frame transverse to the row of characters aside from said end, allowing marking contact of the marking means when across the frame, and allowing increased facility of access to said marking means when moved aside, the mounting by which said base plate is movable comprising members on said base plate extending up astraddle of the frame a distance equal to the major part of the width of the base plate and pivotally connected to the frame near its upper end whereby said base plate may swing up alongside the frame.

3. A marking machine comprising a frame, marking means slidable toward and from the base end of the frame, bearing a row of characters, a base member mounted on said frame to extend across said base end or to move on said frame transverse to the row of characters aside from said end and up alongside said frame, allowing marking contact of the marking means when across the frame, and allowing increased facility of access to said marking means when moved aside, and latching means for said base plate straddling parts of the frame at respective ends of the row of characters and snapping into or out of latching relation to said parts of the frame as said base plate is moved into or out of position across the frame.

4. A marking machine comprising a frame, marking means slidable toward and from the base end of the frame, and a base member mounted on said frame to extend across said base end or to move on said frame aside from said end, allowing marking contact of the marking means when across the frame, and allowing increased facility of access to said marking means when moved aside, the mounting by which said base plate is movable comprising members on said base plate extending up astraddle of the frame and pivotally connected to the frame, and latching means comprising latch members extending up from said base plate astraddle of said frame and having recesses therein, and balls embedded

in the frame, received by the respective recesses by a snap action of said latch member.

5. A marking machine comprising a frame having a slot extending out through its base end, 5 marking means slidable toward and from the base end of the frame and comprising manipulating means extending through said slot and slidable therealong, and a base member mounted on said frame to extend across said base end and slot, or 10 to move on said frame aside from said end and slot, allowing marking contact of the marking means when across the frame, and allowing increased facility of access to said marking means when moved aside, or allowing passage of said 15 manipulating means out through said slot for removal of the marking means from the frame.
6. A marking machine comprising a frame having a slot in one side extending toward the marking end of the machine, a carrier movable 20 toward and from said end, marking means bearing a number of characters and capable of movement on said carrier to selectively dispose the characters toward said marking end, manipulating means connected to said marking means for 25 effecting said movement thereof on the carrier, and extending out through said slot for manipulation and moving along said slot with said marking means and carrier, a handle near the opposite end of said machine, and detent means for 30 holding said marking means in its selected position in said frame, releasable by the hand that holds the handle, while said marking means is selectively moved by the other hand acting on said manipulating means.
35. 7. A marking machine comprising a frame having a slot in one side extending toward the marking end of the machine, a carrier movable toward and from said end, marking means bearing a number of characters and capable of movement on said carrier to selectively dispose the characters toward said marking end, manipulating means connected to said marking means for 40 effecting said movement thereof on the carrier, and extending out through said slot for manipulation and moving along said slot with said marking means and carrier, a handle near the opposite end of said machine, detent means for holding said marking means in its selected position in said frame, releasable by the hand that 45 holds the handle, while said marking means is selectively moved by the other hand acting on said manipulating means, and a base member mounted on said frame to extend across said base end or to move on said frame aside from said 50 end, allowing marking contact of the marking means when across the frame, and allowing increased facility of access to said marking means when moved aside.
8. A marking machine comprising a frame, a 55 marking device movable toward and from the marking end of the machine, an inking device comprising an ink-bearing member mounted to swing outwardly and inwardly away from and toward said marking device, to remove the ink-bearing member from said marking device or apply it thereto, and a roller on said inking device engageable by said marking device to swing said inking device outwardly as the marking device moves toward said marking end of the 60 machine.
9. A marking machine comprising a main frame, a carrier frame movable in said main frame, marking means in said carrier frame, and a shaft extending through said marking 65 means and journaled in opposite sides of said

carrier frame for rotation of said marking means to selective marking positions, said main frame having a slot into which said shaft extends and along which it moves with said main frame, and said shaft having a projection therearound and lying between the slotted part of said main frame and the adjacent side of the carrier frame to limit axial movement of said shaft in said carrier frame.

10. A marking machine comprising a main frame, a carrier frame movable in said main frame, marking means in said carrier frame, and a shaft extending through said, marking means and journaled in opposite sides of said carrier frame for rotation of said marking means to 15 selective marking positions, said main frame having a slot into which said shaft extends and along which it moves with said main frame, and said shaft having a projection therearound and lying between the slotted part of said main frame and the adjacent side of the carrier frame to limit axial movement of said shaft in said carrier frame, said shaft extending out through said slot, and manipulating means on the outwardly extended part of said shaft.

11. A marking machine comprising a main frame having a slot therein extending toward the base end thereof, a carrier frame movable along said slot in said main frame, a shaft journaled in said carrier frame, having a unitary part extending out through said slot, having a key-way in its part that is inside said carrier frame, a series of marking dials coaxially rotatable on the part of said shaft having the key-way, friction washers between the adjacent dials, having unitary engaging projections in said key-way, detent elements operatively mounted on said carrier frame to retentively engage the respective dials or disengage therefrom for rotation of the disengaged dial with the shaft and adjacent friction washers, and manipulating means unitary with the part of said shaft that extends out through said slot.

12. A marking machine comprising a main frame having a slot therein extending toward the base end thereof, a carrier frame movable along said slot in said main frame, a shaft journaled in said carrier frame, extending out through said slot, having a key-way inside said carrier frame, a series of marking dials coaxially rotatable on the part of said shaft having the key-way, friction washers between the adjacent dials, having engaging projections in said key-way, detent elements operatively mounted on said carrier frame to retentively engage the respective dials or disengage therefrom for rotation of the disengaged dial with the shaft and adjacent friction washers, manipulating means on the part of said shaft that extends out through said slot, and a handle on said main frame adapted to be grasped by one hand while said hand selectively manipulates said elements and the other hand rotates said shaft by engaging said manipulating means thereof.

13. A marking machine comprising a main frame having a slot therein extending toward the base end thereof, a carrier frame movable along said slot in said main frame, a shaft journaled in said carrier frame, extending out through said slot, having a key-way inside said carrier frame, a series of marking dials coaxially rotatable on the part of said shaft having the key-way, friction washers between the adjacent dials, having engaging projections in said key-way, detent elements operatively mounted on said car-

rier frame to retentively engage the respective dials or disengage therefrom for rotation of the disengaged dial with the shaft and adjacent friction washers, manipulating means on the part 5 of said shaft that extends out through said slot, a handle on said main frame adapted to be grasped by one hand while said hand selectively manipulates said elements and the other hand rotates said shaft by engaging said manipulating 10 means thereof, and a base member mounted on said frame to extend across said base end or to move on said frame aside from said end, allowing marking contact of the marking means when across the frame, and allowing increased facility 15 of access to said marking means when moved aside.

14. In a marking machine, a frame and a base member connected together near one end of the

frame for relative swinging of said end of the frame and said base member together or apart, and marking means movable on the frame toward and from said end of the frame, with a row of characters arranged along but spaced laterally from the axis of relative swinging of the frame and base member, said base member being constructed to allow contact of the row of characters of said marking member with an object in contact with the base member, for marking the object, when said end of the frame and said base member are swung together, and increased facility of access to said marking means for attention thereto between marking operations being afforded when said end of the frame 15 and said base member are swung apart as aforesaid.

GEORGE STIEGLER.
